UNITED STATES PATENT OFFICE

2,076,663

CUTTING TOOL

Frank P. Miller, Meadville, Pa.

Application April 19, 1935, Serial No. 17,358

12 Claims. (Cl. 77—58)

This invention relates to cutting tools of the type employing inserted blades and the application will be found to feature in part matter divided out of my earlier application, Serial 614,823, which eventuated in Patent Number 2,021,668.

Briefly, the invention provides an inserted blade cutter in which each blade thereof has a dovetail engagement with only one side of the associated blade receiving slot while the other side of the blade extends approximately at right angles to the bottom of the slot and is securely engaged by a locking means by which the blade is held in place, this arrangement allowing increased cross-sectional area and consequently greater strength on the part of the blade and at the same time achieving an addition to the cutting surface of the blade.

Another aspect of the invention has to do with the blade locking means which will be found to provide for urging the blade locking pin thereof inward or in the same direction that the blade is urged by the end thrust accompanying operation, as distinguished from other cutters in which the blade locking means acts in opposition to the thrust of the cut and for that reason does not operate with maximum efficiency in securing the blade in adjusted position.

The invention also contemplates a novel mounting for a blade adjusting screw and by way of brief preliminary reference to this phase of the invention it is pointed out that the socket or opening in the cutter body for the reception of the screw breaks through one corner of the blade receiving slot, as distinguished from breaking through only one side wall thereof with the result that in all operative positions of the screw, the screw has a generous interlocking engagement with the body of the cutter while at the same time the longitudinal center of the screw is located in the slot for pressure relation with the associated blade. In addition, the mounting for the blade adjusting screw provides for relatively increased blade travel or adjustment and thus obtains maximum use of the costly metal comprising the blade.

Other objects and advantages will be apparent during the course of the following description.

In the accompanying drawing, forming a part of this application and in which like numerals are employed to designate like parts throughout the same,

Figure 1 is a group perspective of a cutter block embodying the invention,

Figure 2 is a plan view of the cutter block, a portion of the block being broken away,

Figure 3 is a vertical transverse sectional view taken on line 3—3 of Figure 2,

Figure 4 is a detail transverse sectional view taken on line 4—4 of Figure 2,

Figure 5 is a fragmentary plan view disclosing a modification of the invention,

Figure 6 is a detail transverse sectional view taken on line 6—6 of Figure 5,

Figure 7 is a detail transverse sectional view disclosing another expression of the invention,

Figure 8 is a perspective of a threaded bushing shown in section in Figure 7.

In the drawing, wherein for the purpose of illustration are shown several preferred embodiments of the invention, the numeral 10 designates a cutter block of the type adapted to be mounted in a boring bar or other support. As shown in Figures 1 and 2 the body 10 is formed in opposite sides thereof with diagonally extending slots 12 opening out through the opposite terminals of the body for the reception of blades 14.

It is illustrated in Figures 3 and 4 that one longitudinal side of each blade 14 has a dove-tailed contact 16 with the opposed side wall of the associated slot, while the other longitudinal side or edge of the blade is lacking in such dove-tailed fit, and in fact, extends approximately at right angles to the surface plane of the block and to the bottom wall of the associated slot, giving to the blade a greater cross-sectional area and providing a longer facing or cutting edge than is the case where the blade is dove-tailed on both sides.

That side of the blade 14 which extends at right angles to the plane or surface of the block and to the bottom wall of the associated slot is formed with a longitudinal groove 20 mating with a more or less similar groove 22 in the opposed side wall of the slot 12 for the reception of a cylindrical locking pin 26.

Referring now to Figure 3, it will be seen that a locking screw 30 is threaded through the block at the front side of the associated blade and is provided between the ends thereof with an annular groove 32 defining a transversely curved annular shoulder for pressure contact with the adjacent locking pin 26. Thus, advancement of the screw 30 brings about transverse movement of the locking pin into binding engagement with the associated blade.

Now, it is also clearly illustrated in Figure 3 that the forward portion of the set screw 30 is provided with left-hand screw threads which are, of course, the reverse of the threads ordinarily found on the corresponding parts in inserted blade cutting tools. This arrangement requires

that advancement of the set screw be brought about by the left-hand turning of the screw. Such left-hand turning of the set screw has the effect of moving laterally the adjacent locking pin and at the same time urging the pin inwardly or rearwardly, thereby exerting a rearward or seating force on the associated blade. The force thus applied to the blade acts in the same direction as the end thrust of the cut and thus acts 10 in concert with such thrust as distinguished from the outward and unseating influence exerted by a right hand thread on the screw.

The forward portion of the set screw 30 is shown to be provided with a tool engaging means 15 in the nature of a screw driver groove 38 so that even though the set screw has a left-hand thread, advancement of the screw is conveniently accomplished by turning the screw driver to the right as is customary.

20 As shown in Figures 1 and 2, each blade is engaged at the rear end thereof by a thrust screw 50 and such thrust screw is threaded into an opening or socket 52 in the block. It is important to observe that the opening 52 opens for 25 substantially less than 90 degrees into the block 12 so that the set screw is prevented from shifting laterally from the socket 52 into the blade slot.

Attention is invited to Figure 2 in which it is 30 illustrated that the opening or socket 52 breaks through that longitudinal corner of the blade slot 12 in which the walls of such corner are at an acute angle to each other. Hence, while less than a quarter of the circumference of the screw 35 is exposed and left without bracing, substantially more than a quarter of the cross-sectional area of the screw, including the axial center of the screw is in the slot for pressure engagement at the forward end thereof with the blade. This 40 arrangement leaves substantially more than 270 degrees of the threaded circumference of the screw in thrust transmitting interlocking engagement with the surrounding wall of the socket 52.

45 Also, by causing the opening 52 to break through adjoining walls of the slot, as distinguished from breaking through but one wall, there is avoided appreciable weakening of the block due to the presence of the opening.

50 The mounting of the screw 50 holds the screw in full functioning position even though it has been adjusted far beyond its original position and has come to be located between the ends 55 of the blade receiving slot. That is to say, the break in the side wall of the socket or hole 52 is less than 90° leaving substantially more than 270° of the circumference of the screw surrounded and in intimate threaded engagement 60 with the material forming the block. By reason of this arrangement, the screw is positively held against lateral slipping or shifting into the blade receiving slot or losing the intended close fit with the surrounding threads, this being true regardless of the position to which the screw is advanced. This blade mounting is particularly advantageous not only because of the security with 65 which the screw is held in place, but also since it makes possible an unusual amount of blade adjustment and wear. That is to say, regardless of the adjustment of the screw or the extent to which it is advanced, it remains in functioning position in full threaded engagement for substantially the entire length thereof with the 70 rounding wall of the socket 52.

In summarizing it will be seen that the tool is in the nature of a cutter block in which body thereof has one or more slots provided with inner end and front and back sides, and that a blade is adjustably positioned in each slot and 5 has leading and trailing sides and further that the locking pin 26 engages the leading side of the blade under the force of a binding screw located adjacent the front side of the slot and engaging the pin at a point between the ends 10 of the slot, the body and the screw having interfitting left hand threads necessitating counterclockwise rotation of the screw to advance the screw and turn the screw in the direction necessary to urge the locking pin and the blade toward the said inner end wall of the slot while at the same time, forcing the trailing side of the blade firmly against the back side of the slot. That is to say, by this arrangement, the trailing 15 side of the blade has effective thrust transmitting contact with the back side of the slot and at the same time the screw is turned in a counterclockwise direction to advance the screw and thus force the pin 26 laterally and rearwardly, thereby urging the blade rearwardly or in the same direction in which it is urged under the influence of the end thrust accompanying operation. Clearly, it is not feasible to locate the 20 binding screw adjacent the trailing side of the blade because it is required that there be a firm thrust transmitting contact between the back side of the blade and the back side of the slot.

25 In the form of invention disclosed in Figures 5 and 6 the block is designated by the numeral 35 80 and is provided with a slot 82 for the adjustable reception of a blade 84. In this form of invention the cross-sectional form of the blade and the slot may be the same as that shown in Figures 1 to 4 inclusive. One side wall of the 40 slot 82 is formed with a recess 86 receiving a locking bushing 88 of segmental form and having a flat side presented to the blade and formed with a rib 90 projecting into a groove in the adjacent side of the blade. A set screw 92 may be 45 employed to secure the bushing 88 in firm, locking engagement with the blade. It will be seen that the rib 90 functions after the fashion of the pin 26 shown in Figures 1 to 4 and thus serves as a pressure transmitting medium between the 50 bushing 88 and the adjacent blade, urging the blade laterally and inward into pressure contact with the back and bottom walls of the slot.

55 In Figure 7, one side of the blade 100 is formed with a groove 102 having a more or less flattened or inclined lower wall defining a cam-like surface for engagement by the rib 104 of the associated locking bushing 106.

Having thus described the invention what is 60 claimed is:

1. A tool carrying block for use in a boring bar comprising a body having a slot provided with longitudinal walls at acute angles to each other thereby defining a longitudinal corner, a blade in said slot, said body being formed with a threaded opening overlapping the slot and extending along said longitudinal corner, and an axially adjustable screw in said opening and having more than 270 degrees of the circumference thereof surrounded by the wall of said threaded opening and having more than a quarter of the cross-sectional area thereof in said slot the forward end of the said screw being in abutting relation to the inner end of said blade.

2. A tool carrying block for use in a boring bar 75

comprising a body having a slot provided with walls at acute angles to each other thereby defining a corner, a cutting blade in said slot, said body being formed with a threaded opening overlapping the slot and extending along said corner, and an axially adjustable screw in said threaded opening and having more than 270 degrees of the circumference thereof surrounded by the wall of said opening and having more than a quarter 5 of the cross-sectional area thereof in said slot, and having the axial center thereof in said slot the forward end of said screw being in abutting relation to the inner end of said blade.

3. A tool carrying block for use in a boring bar 15 comprising a body having a slot provided with side and bottom longitudinal walls defining a longitudinal corner, a blade in said slot, said body being provided with a threaded opening breaking through and extending along said longitudinal corner, and an axially adjustable screw 20 in said opening and having more than 270 degrees of the circumference thereof surrounded for the full length thereof by the wall of said threaded opening and having the axial center 25 thereof in said slot, the forward end of said screw being in abutting relation to the inner end of said blade.

4. In a block for use in a boring bar, a body 30 having a slot provided with side and bottom longitudinal walls defining a longitudinal corner, a blade in said slot, said body being provided with a threaded opening overlapping and extending along said longitudinal corner, and an axially adjustable screw in said threaded opening and 35 engaged for the full length thereof by the wall of said opening, said screw being extended into said slot in abutting relation to the inner end of said blade.

5. A tool carrying block for use in a boring bar 40 comprising, a body having a slot provided with an inner end and front and back sides, a blade in said slot and having leading and trailing sides, locking pin engaging the leading side of the blade, and a binding screw adjacent to 45 the front side of the slot and engaging the pin at a point between the ends of the slot, said body and said screw having interfitting left hand threads necessitating counter-clockwise rotation of the screw to advance the screw and turn the 50 pin side of the screw in the direction of the said inner end of the slot and thus urge the locking pin and the blade toward the said inner end of the slot and simultaneously force the trailing side of the blade firmly against the back side of 55 the slot, the forward portion of said binding screw being provided with means for engagement by an operating tool.

6. In a block for use in a boring bar, a body 60 having blade receiving slots disposed diagonally to the axis of the block, each of said slots being provided with a bottom wall and back and front side walls, the back side wall being at an acute angle to the bottom wall and the front side wall being at right angles to the bottom wall, blades 65 in said slots which in cross-section conform to the cross-sectional form of said slots, and locking means for each of said blades embodying a locking pin engaging the front side of the blade and a binding screw adjacent to the front wall 70 of the slot and engaging the pin at a point between the ends of the slot, said body and said screw having interfitting left-hand threads whereby advance of the screw will result in turning of the pin side thereof in the direction of 75 the inner end of the slot to urge the locking pin

and the blade toward the inner end of the slot and simultaneously force the back side of the blade firmly against the back wall of the slot, the forward portion of said screw being provided with means for engagement by an operating tool.

7. A tool carrying block for use in a boring bar, 5 comprising a body having upper and lower sides and a blade receiving slot opening through one of said sides, said slot being provided with front and back longitudinal side walls, a blade in said slot and having leading and trailing sides, the leading side of said blade and the front wall of the slot being formed with cooperating grooves, a locking pin in said grooves, and a binding screw engaging said locking pin at a point between the ends thereof, said binding screw and said body being formed with interfitting lefthand threads, the forward portion of said screw being provided with means for engagement by an operating tool for turning the screw, said means being 10 accessible from the side of said body opposite that having the blade receiving slot therein.

8. A tool carrying block for use in a boring bar comprising a body having a blade receiving slot disposed diagonally to the axis of the body and opening through one side thereof, a blade in said slot, said blade being provided with a groove along the front side thereof, a clamping member engaging said groove, and threaded means for actuating said clamping member, said threaded means being provided with a tool engaging portion accessible for operation from the side of said body opposite that having the blade receiving slot therein.

9. A tool carrying block for use in a boring bar 15 comprising a body having a blade receiving slot opening through one side thereof, said slot being provided with front and back longitudinal side walls and a bottom wall, the back side wall of said slot being at an acute angle to the bottom wall and the front wall being at right angles to the bottom wall, a blade in said slot which in cross-section conforms to the cross-sectional form of the slot, said blade being provided with a groove along the front side thereof, a clamping member engaging said groove, and threaded means for actuating said clamping member, said threaded means being provided with a tool engaging portion accessible for operation from the side of said body opposite that having the blade 20 receiving slot therein.

10. A tool carrying block for use in a boring bar 25 comprising a body having a blade receiving slot opening through one side of the body, said slot being provided with front and back longitudinal side walls, a blade in said slot and having leading and trailing sides, the leading side of said blade being provided with a groove extending lengthwise of the blade, said body being provided at the front side of said slot with a socket 30 opening into the slot, a locking bushing in said socket and having a rib projecting into the groove in said blade, and a locking screw extending into said body from the side opposite that containing the blade receiving slot and having threaded engagement with said bushing.

11. A tool carrying block for use in a boring bar 35 comprising a body having a blade receiving slot opening through one side of the body, said slot being provided with front and back longitudinal side walls, a blade in said slot and having leading and trailing sides, the leading side of said blade being provided with a groove extending lengthwise of the blade, the lower wall of said 40 groove being inclined to define a cam-like sur- 45

face, said body being provided at the front side of said slot with a socket opening into the slot, a locking bushing in said socket and having a rib projecting into the groove in said blade and engaging said cam-like surface, and a locking screw extending into said body from the side opposite that containing the blade receiving slot and having threaded engagement with said bushing.

12. In a block for use in a boring bar, a body 10 having a blade receiving slot provided with front and back longitudinal side walls and a bottom

wall, a blade in said slot, the front longitudinal side wall of said blade being formed with a groove running lengthwise thereof, a locking element projecting into said groove, and a binding screw threaded into said body and engaged with said locking element to urge the locking element and the blade downwardly toward the bottom wall of said slot, laterally toward said back longitudinal side wall of the slot and in the direction of the inner end of the slot. 5

FRANK P. MILLER.
